UNITED STATES PATENT OFFICE.

MAX E. MELTON, OF WASHINGTON, DISTRICT OF COLUMBIA, ASSIGNOR TO UNDERWOOD TYPEWRITER COMPANY, OF NEW YORK, N. Y., A CORPORATION OF DELAWARE.

TYPEWRITING-MACHINE.

1,333,931.

Specification of Letters Patent. Patented Mar. 16, 1920.

Original application filed April 26, 1916, Serial No. 93,575. Divided and this application filed October 2, 1916. Serial No. 123,238.

To all whom it may concern:

Be it known that I, MAX E. MELTON, a citizen of the United States, residing in Washington, District of Columbia, have invented certain new and useful Improvements in Typewriting-Machines, of which the following is a specification.

This invention relates to typewriting machines and more particularly to paper-roll carrying means for the same.

In machines of this character, it is sometimes desirable to provide the work-sheets in the form of a continuous web of paper wound on spools or rolls. These webs are fed together into the machine and around the platen to receive type impressions. The sheets or webs may be superposed with webs of carbon paper or with inking ribbon at the printing line of the machine.

In practice, it is frequently desirable to use paper of different widths, at different times, and also to write at different positions along the platen, and accordingly, the mechanism for holding the roll has been made adjustable so as to accommodate paper of various widths and so as to be adjustable lengthwise of the platen; and, where a plurality of rolls were used, such changes have required the adjustment of each individual holding means for each individual roll. I have found it advantageous to provide supporting means having individual supports or journals for the several rolls, said supporting means being adjustable to effect a simultaneous adjustment of the journals for all the rolls. These means may comprise a set of roll-carrying studs mounted on a pair of side-plates, adjustably mounted in the roll-support proper so that by adjusting either or both the side plates, all of the studs on each plate will be moved together, thereby changing the width between them. These side-plates may be slidably mounted on a roll-carrying frame proper and adapted to be held in adjusted position by said screws.

This construction permits a frame to be built of a size which will exactly adjust itself to a standard typewriting machine, and also permits the webs or rolls to be adjusted along said support for the purposes mentioned above.

This application is a division of my co-

pending application Serial Number 93,575, filed April 26, 1916.

Other features and advantages will hereinafter appear.

In the accompanying drawings:

Figure 1 is a part sectional end elevation of a typewriting machine, with the present invention applied thereto.

Fig. 2 is a part sectional elevation on a larger scale, partly diagrammatic, showing the webs fed around the platen.

Fig. 3 is a plan view showing the construction of the roll holding stub shaft.

Fig. 4 is a rear elevation of the machine.

The invention is shown as applied to an Underwood typewriting machine. Keys 10, fulcrumed at 11, operate through bell cranks 12 to swing type-bars 13 upwardly and rearwardly about a fulcrum 14 and cause the types 15 to strike against the front face of the roller platen 16. The platen axle 17 is journaled in the ends 18 and 19 of the platen frame, the latter also including an inclined paper shelf 20 connecting the frame ends, said shelf located at the rear of the platen for supporting and guiding the work to the platen.

The platen may be rotated by hand wheels 21 on the platen axle. The line-spacing mechanism for rotating the platen to line-space the work, comprises a line-space lever 22 (Fig. 1), operable to move rearwardly a slide 23 carrying a driving pawl 24 to drive a line-space ratchet wheel 25 fixed to the platen axle, to thereby effect line-space rotations of the platen. The platen frame is mounted on a carriage 26, being shiftable up and down thereon to upper and lower-case positions, by means of the usual platen shifting mechanism. The carriage is mounted to travel horizontally on front and rear guide rails 27 and 28, and is driven in letter-feed direction by the usual spring drum 29 (Fig. 4), connected through a band 30 to the carriage.

The letter-feed movements of the carriage are controlled by the usual mechanism, comprising a rack 31 (Fig. 1) on the carriage running in mesh with an escapement pinion 32 which drives an escapement wheel 33 with which co-operate escapement dogs 34 on a dog rocker 35. The dog rocker is actuated by a universal bar 36

which, at each type stroke, is moved rearwardly by a shoulder 37 on the operated type-bar, permitting a letter-space movement of the carriage at each type stroke.

5 Ribbon mechanism for vibrating a ribbon 38 (Fig. 2) over the printing point at each type stroke, may comprise a ribbon vibrator 39 through which the ribbon is guided, said mechanism being operated in 10 the usual manner. The parts above described may be those usual to the commercial Underwood typewriting machine.

The paper strips or webs 40 on which manifolding is done are wound on supply 15 rolls 41 removably mounted on a truck 42 arranged to travel with the carriage. As shown, the truck comprises a frame having open rectangular frame ends 43 connected by tie rods 44 extending between the 20 corners of the frame ends. The skeleton frame thus constructed is strong and rigid and at the same time is light in weight and has little inertia, so that it does not materially impede the letter-feed movements 25 of the carriage.

The rolls 41 are supported between plates 45 mounted on the rods 44 and adjustable lengthwise of the rods, permitting adjustment of said plates to rolls of different 30 lengths, and also permitting adjustment of the rolls to any desired position lengthwise of the platen. The rods 44 may extend through collars 46 fixed to said plates, and provided with set screws 47 by which the 35 plates may be clamped in their adjusted positions on said rods. The paper rolls 41 may be mounted on spools or cores 48 (Fig. 4). Each spool is provided at each end with a central bore or socket to 40 receive stub shafts 49, on which the spool is journaled, said shafts 49 being mounted for endwise movement in the plates 45, into and out of spool-holding position. Said 45 stub shafts may be slidable endwise in bearing sleeves 50 fixed in the plates 45 and each provided with a bayonet slot 51 in which works a pin 52 on the shaft, whereby said shaft may be locked in its spool-holding position. With this construction any 50 roll may be quickly placed in position or removed without interference with the other rolls.

The roll-holding frame or truck is arranged to travel with the carriage 26, so 55 that the rolls may be maintained in operative relation to the platen. For this purpose the truck 42 is mounted to travel on a track comprising an angle-bar 53 located behind the main frame 54 of the machine. 60 Said track is removably mounted on the machine frame by means of brackets 55 which are rigidly connected with the track 53 by horizontal arms 56. The track may be removed from the machine by simply 65 lifting the brackets 55 off the machine

frame. The weight of the roll-holding frame is supported on truck wheels 57 which run on the track 53. Said wheels are prevented from moving rearwardly off the track by a guard rail 58. Horizontal 70 guide rolls 59 are arranged to run on the vertical member of the angle-bar 53.

The roll-holding frame 42 is connected to the type-writer carriage by arms 60, which may be pivoted at 61 to the upper 75 rear corner of the frame, said arms extending forwardly and downwardly from their pivots, and being provided at their forward ends with hooks 62 to engage a shaft 63, which forms part of an Underwood carriage, and is journaled in fixed bearings thereon. The hooks 62 may be held against outward movement lengthwise of the shaft 63 by sleeves 64 on said shaft, and are also rigidly held against the usual 80 inward movement along said shaft as they bear against the ends 43 of the roll frame. That is to say, the arms 60 are securely held against endwise play or movement in either direction relative to the roll frame, and 85 endwise movement of the roll frame relative to the platen is also prevented. The webs are thus maintained in a position normal to the platen.

The webs of paper from the rolls 41 are 90 led forward over the rolled or beaded upper edge 65 of the paper shelf 20, which serves as an assembling guide for the webs, the latter being directed downward over the paper table and between the platen and 100 the rear and front feed rolls 66 and 67, and thence upwardly past the printing line. The ribbon 38, above referred to, may serve for printing on the outer web, or on a work-sheet which may overlie the webs 105 at the printing line. The printing on the other webs may be caused by carbon webs wound or certain of the rolls 41 or by any other suitable manifold material in any suitable manner.

By having the axes of the rolls staggered or offset from each other in the manner shown, it is possible to have the weight on the roll-carriage so low that there is little or no tendency for the roll-carriage to 115 rock endwise, as would be the case were the rolls directly above each other. It is this having the weight low which largely makes possible the simple detachable connection between the typewriter carriage and 120 the roll-carriage.

Variations may be resorted to within the scope of the invention, and portions of the improvements may be used without others.

Having thus described my invention, I 125 claim:

1. A roll-support adapted to coöperate with a typewriting machine, comprising a track adapted to fit over and be held by its own weight on the frame of said typewriting 130

machine, a roll-carrying frame forming a carriage and adapted to travel on said track, roll-supporting plates adjustable along said roll-carrying frame to fit rolls of various 5 lengths, and comprising journals for the rolls, swinging arms comprising hooks adapted to swing over and latch themselves to members on the carriage of said typewriting machine, to carry the roll-carrying 10 frame along with said typewriter carriage, and a plurality of rolls journaled in said plates, the journals for adjacent rolls being offset from each other to permit the rolls to be carried low down on the plates and near 15 the carriage.

2. A roll-support adapted to coöperate with a typewriting machine, comprising a track adapted to fit over and be held by its own weight on the frame of said typewriting 20 machine, a framework forming a roll-carriage and adapted to travel on said track, rods fixed to and connecting the ends of said framework, roll-supporting members slideable on said rods, journals on said roll-supporting 25 members and offset from each other to permit rolls journaled thereon to be carried low down and near the carriage, and arms on said framework adapted to be swung to latch themselves on a part of the typewriter carriage, to carry the framework along with the typewriter carriage.

3. A roll-support adapted to coöperate with a typewriting machine, comprising a track adapted to fit over and be held by its own weight on the frame of said typewriting 35 machine, a framework forming a carriage and adapted to travel on said track, rods fixed to and connecting the ends of said framework, roll-supporting members slideable on said rods, journals on said roll-supporting members in pairs adapted to hold the rolls, arms adapted to be swung on said framework to latch themselves on a part of the carriage of said typewriter and carry 40 said framework along with said typewriter carriage, set screws for adjustably setting said roll-carrying members independently on said rods, and stud shafts adapted to support rolls on said members.

50 4. A roll-support adapted to coöperate with a typewriting machine, comprising a track adapted to fit the frame of said machine, a roll-carrying frame forming a carriage adapted to travel on said track, roll-supports adjustable along said frame, journals set low down on said supports to bring 55 the weight of the rolls near the track, and

offset from each other to enable them to carry the rolls near the typewriter carriage, and swinging arms pivoted on said frame 60 adapted to latch themselves to a shaft on said typewriter to carry the roll-carrying frame along with said carriage.

5. A roll-support adapted to coöperate with a typewriting machine, comprising a track adapted to fit and rest on the frame of said typewriting machine, a roll-carrying frame having substantially the width of the platen of the typewriter carriage, an arm on each end of said frame adapted to be swung 65 to latch itself to the carriage to cause the frame to travel with the carriage, hooks on said arms forming the latches and so holding said frame, and adapted to bear against sleeves to hold it against sliding, so that the 70 typewriter carriage and the frame travel together, roll-holding members independently adjustable on said frame, and removable stud shafts in said roll-holders adapted to support rolls therein near the track, said 75 stud shafts offset from each other vertically to permit the rolls to be carried near the carriage.

6. A roll-support adapted to coöperate with a typewriting machine, comprising a track adapted to fit and rest on the frame of said machine, a roll-carrying frame, bars forming the ends of said frame, rods connecting the opposite ends of the frame, swinging arms on said frame comprising 85 hooks adapted to swing over and latch themselves to a substantially fixed shaft on the carriage of the typewriter and to engage abutments on said shaft to cause the frame to travel with the carriage of the typewriter, pivots for said arms remote from the typewriter, a pair of roll-supporting members slideable on said rods, means for locking each roll-supporting member independently to the rods, stud shafts in each roll-supporting member for the rolls adapted to be supported thereby, said stud shafts offset from each other vertically to bring the weight of the rolls near the track and near the typewriter carriage, a boss on each member for each stud shaft thereon, and connections whereby each stud shaft may be independently withdrawn to engage a roll therewith.

MAX E. MELTON.
